UNITED STATES PATENT OFFICE.

ARTHUR EDWARD POHLMAN, OF WATERTOWN, WISCONSIN.

COMBINATION FLOWER-POT AND REFLECTOR.

1,215,986.

Specification of Letters Patent. Patented Feb. 13, 1917.

Application filed June 26, 1916. Serial No. 105,988.

To all whom it may concern:

Be it known that I, ARTHUR E. POHLMAN, a citizen of the United States, and a resident of Watertown, in the county of Jefferson and 5 State of Wisconsin, have invented a new and Improved Combination Flower-Pot and Reflector, of which the following is a full, clear, and exact description.

General objects of my invention are to 10 provide a lamp with a reflector and globe so arranged as to result in an effective lighting of a room, and so combine a flower pot with the lamp as to improve the appearance of the latter; and to provide ample space for 15 earth or water, or both, between the reflector and a shell member, or members.

More specific objects of the invention are 20 to provide a structure of the indicated class of a durable character to give the structure a desirable form esthetically, and to provide a construction affording ready access to the different parts for the renewal, repair, or cleaning.

Other objects of the invention will appear 25 as the description proceeds.

Reference is to be had to the accompanying drawings forming a part of this specification in which the figure is a vertical section of a flower pot embodying my invention.

In constructing a practical embodiment 30 of my invention, an outer shell 10^d is provided, which preferably flares in an upward direction from the bottom. Within the shell 35 10^d is a reflector 11^d in the form of an inner shell of inverted, truncated cone shape.

On the bottom of the structure I provide 40 supporting means for a source of light; preferably, a socket 22 is provided, which is of a character to receive an electric lamp 23, the numeral 24 indicating the conductor for the lamp.

The described arrangement gives considerable space within the shell 10^d and outside 45 of the reflector 11^d for containing an ample quantity of earth, indicated by the letter A^d, so that provision is made for plants affording a proper display in a comparatively small structure.

50 In order to provide for a continuously moistening of the earth A^d and regulate the supply of moisture thereto, an annular par-

tition 28^d is arranged in connection with the outer shell 10, thus forming between the same and the reflector an annular reservoir, 55 adapted to contain water as indicated at B^d.

An inverted glass globe 46 is arranged to inclose the flower pot structure at the bottom and sides. It may be suspended from the chains 25 by the means illustrated in which 60 lugs 47 are formed on a ring 48, which is of a size to form a rest for the bead 49 of the globe. Any suitable connection may be provided between the flower pot structure and the ring 48, there being shown snaphooks 50 65 rigid with the outer shell 10^d and adapted to engage in slots 51 in the lugs 47 which slots also receive the bottom links of the hanger chains 25.

The reflector 11^d has an open bottom and 70 the socket 22 for the lamp 23 rests on a seat 52 which is carried by brackets 53, secured to the under side of the flower pot structure as at 54, the said seat being disposed below the bottom of the reflector. The arrangement 75 is such that light from the lamp 23 will not only be reflected upwardly by the reflector 11^d, but will also illuminate the globe 46, which, in practice, will be translucent. The partition 28^d is spaced from the 80 reflector 11^d by a flanged top ring 40^d. The water compartment and the earth compartment are closed at the bottom and on the bottom of the water compartment is a felt ring 31^d adjacent to lateral water outlets 32^d 85 in the shell 28^d so that moisture will slowly find its way to the earth compartment. The numeral 42^d indicates a capped filling neck and 43^d a vent in the ring 40^d at the top of the water compartment.

Having thus described my invention I 90 claim as new, and desire to secure by Letters Patent:

A device of the character described, including an upwardly disposed reflector, an 95 annular flower pot structure surrounding the reflector, and means to support a source of light approximately central of the reflector; together with a glass bowl extending around and beneath the flower pot structure adapted to receive the light rays from the source of light in the reflector.

ARTHUR EDWARD POHLMAN.
